UNITED STATES PATENT OFFICE.

JOHN A. SWORD, OF ABILENE, KANSAS.

BINDER-TRIP FOR HARVESTERS.

1,197,968.

Specification of Letters Patent. Patented Sept. 12, 1916.

Application filed August 11, 1915. Serial No. 44,967.

To all whom it may concern:

Be it known that I, JOHN A. SWORD, a citizen of the United States, residing at Abilene, in the county of Dickinson, State of Kansas, have invented certain new and useful Improvements in Binder-Trips for Harvesters; and I do hereby declare the following to be a full, clear, and exact description of the invention, such as will enable others skilled in the art to which it appertains to make and use the same.

This invention relates to new and useful improvements in harvesting machines and is particularly directed to the provision of trip means for the binder mechanism thereof.

Much inconvenience is encountered in the operation of harvesting machines including binders in that the trip mechanism for said binders sometimes becomes stuck or otherwise fails to work, or sometimes an excess of grain is encountered which clogs the

It is therefore the object of the present invention to provide a manually operated means for positively actuating the trip mechanism at will by the operator sitting on the seat of the machine.

It is further an object to provide such a device which may be readily attached to harvesting machines of standard types now on the market, and wherein means are provided for the shifting of the binder mechanism with relation to the body of the machine.

With the above and other objects and advantages in view, the invention resides more particularly in the novel combination, for- mation and arrangement of parts as more fully described hereinafter and pointed out in the appended claims.

Reference is had to the accompanying drawings, wherein similar characters of reference designate corresponding parts throughout the several views, in which:

Figure 1 is a top plan view of a portion of a harvesting machine of conventional type having associated therewith the improved manually operated means for actuating the tripping mechanism. Fig. 2 is a view showing the seat pipe of the machine and the portion of the improved device carried thereby in side elevation. Fig. 3 is a front elevational view of the structure shown in Fig. 1. Fig. 4 is a perspective view of the forward end of the binder pipe and the improved mechanism carried thereby. Fig.

5 is a sectional view on the line 5—5 of Fig. 1. Fig. 6 is a detail sectional view taken through the adjustable connection between the foot lever of the device and the link extending therefrom.

Referring now more particularly to the accompanying drawings, the harvester with which the present manual tripping mechanism is associated is of the general conventional type found in Dearing harvesting machines and includes the main cutter frame

5 which has at one forward corner a depending bearing 6, in which is slidably mounted the binder pipe 7 which is shiftable in operation of the binder mechanism. Ex-

tending over the frame 5 is the seat pipe 8 carrying the seat 9, and this pipe terminates adjacent and above the forward end of the frame 5. There is also shown at 10 a portion of the elevator frame. Associated with

the binder mechanism of the machine is the usual automatic trip mechanism, the only part of which being shown is the trip shaft

11 journaled in suitable bearings 12 which are adapted to depend from the binder structure, the shaft carrying at its forward end an off-set or crank portion 13. The im-

proved means associated with this structure whereby the trip shaft 11 may be rocked to trip the binder, by the operator from the seat on the machine, comprises a squared shaft 14 which has its ends rounded and journaled in arms 15 upstanding from the

forward portion of the binder pipe 7, the forward of these arms 15 having a lateral

attaching portion 16 slotted to receive the securing bolt 17 thereof, whereby adjustment may be had to properly adjust the bearings with relation to the shaft. An arm

18 upstands from the forward portion of the shaft and pivotally connected to this arm is one end of a link 19 which has its other end bent to form a loop 20 in which is engaged the crank portion 13 of the trip shaft

11, said crank portion normally lying in the outer portion of the loop so that it has free movement to permit the normal automatic action of the binder trip. For rocking the shaft 14 to thus rock the binder shaft by

means carried on the frame a sleeve 21 having a square bore is slidable on the shaft inwardly of the arm 18 and the forward end of this sleeve carries an upwardly and forwardly extending arm 22. As stated the binder pipe 7 moves with relation to the frame and to hold the sleeve 21 against such

movement on the shaft 14 which is carried by said pipe, to prevent distortion of the actuating means carried by the frame a plate 23 is adjustably secured on the end of the frame by a bolt 24 passed through a vertical slot 25, and this plate carries a downwardly and outwardly extending arm 26 which has its free end curved at 27 to seat on the sleeve. This curved end is disposed 10 between the arm 22 and upstanding flange 28 at the other end of the sleeve whereby the sleeve is held against sliding in either direction. The means for rocking this arm 22 includes a foot lever 29 which is intermediately pivoted to the pipe 8 forwardly of the seat and carries at its upper end the foot plate 30. The lower end of this lever is pivoted between the bifurcated ends 31 of a socket member 32 in which is threadedly engaged 15 one end of a link 33 which extends forwardly over the frame.

An upstanding arm 34 is secured at the forward end of the seat pipe 8 by providing it with a plug 35 screwed in said end of the pipe and pivoted to the upper end of this arm is an angle lever 36 which lies in a horizontal plane and which has pivotally secured to one of its arms the forward end of the link 33. A link 37 connects the other arm 20 of the lever to the arm 22 whereby when the foot lever 29 is rocked, said arm 22 will be rocked to rock the shaft 14 and consequently rock the binder trip shaft 11. The structure described is held in normal inoperative 25 position by a spring 38 secured to the last named arm of the angle lever 36 and to a hook 39 carried on the elevator frame 10.

From the foregoing description it is observed that a comparatively simple structure 30 has been provided, which may be readily attached to a conventional type of harvester to efficiently perform the functions set forth and without interfering in any manner with the normal operation of the trip mechanism or any other part of the machine. Adjustment of the device may be had by adjusting the link 33 in the socket member 32.

While I have illustrated and described a particular embodiment of my invention, 35 I have merely done so for the sake of convenience and I do not wish to be limited to that particular embodiment as it is obvious that numerous changes may be made within the details of construction thereof without 40 in any way departing from the spirit of the invention or exceeding the scope of the invention as claimed.

Copies of this patent may be obtained for five cents each, by addressing the "Commissioner of Patents, Washington, D. C."

While the arms 15 which support the shaft 14 are described as extending upwardly, said arms to meet other conditions 60 of service, may extend horizontally from the pipe 7, with slight changes in the proportions of the various parts.

What I claim is:

1. In a binder including a frame, a shift- 65 able pipe, and a trip shaft having a crank; means to operate the trip shaft controlled by the operator of the binder and comprising a lever pivoted intermediate its ends to a fixed part of the binder, a pedal on said lever within reach of the operator, a bell crank lever pivoted at its angle to a fixed 70 binder part, a rod connecting the first lever to one arm of the bell crank lever, bearings fixed on the pipe, and movable therewith, a 75 polygonal rock shaft having journal ends mounted in said bearings, a rock arm fixed on said shaft, a link having one end pivoted to said rock arm and provided at its other end with a slot receiving said crank, a sleeve 80 having a polygonal bore slidably fitting said rock shaft, a second rock arm carried by said sleeve, a link connecting the second rock arm and the remaining arm of the bell crank lever, said sleeve having a collar at one end, 85 an arm fixed to said frame and having a curved plate at its free end fitting the sleeve between the collar and the second rock arm, and a spring having one end connected to the bell crank lever and its other end connected to a fixed binder part to hold the 90 parts normally in inoperative position.

2. In a binder including a frame, a shift- 95 able pipe and a trip shaft having a crank; means to operate the trip shaft including an operator's lever, a rock shaft journaled on the pipe, a rock arm on said shaft, a link connecting said crank and rock arm and arranged to permit movement of the crank independently of the link and to move the 100 crank as the link is moved, a sleeve splined on said pipe, a rock arm fixed to said sleeve, means to hold the sleeve against longitudinal movement relative to the frame, an operative connection between the lever and 105 second rock arm, and spring means normally holding the link in inoperative position.

In testimony whereof, I affix my signature, in the presence of two witnesses.

JOHN A. SWORD.
